IMPACT CRUSHER

Oscar C. Gruender, Milwaukee, Wis., assignor to
 Nordberg Manufacturing Co., Milwaukee, Wis.,
 a corporation of Wisconsin

Application September 13, 1935, Serial No. 40,430

10 Claims. (Cl. 83—46)

My invention relates to an improvement in impact crushers. One purpose is the provision of an impact crusher having a low power consumption. Another purpose is the provision of a compact and unitary apparatus which will occupy a minimum of space. Another object is to avoid the use of reduction gears or belts. Another object is the construction of a housing with provision for ready access to impeller and breaker plates as well as to liners. Another object is to provide several means for the attachment of breaker plates to the impeller, whereby the breaker plates are easily applied or removed and firmly held. Another object is the provision of the use of breaker plates at such an angle as to cause the particles to be thrust against the liners or intercepting plates along a horizontal direction, thereby increasing the impacting effect. Another object is the prevention of the entry of dust into the main shaft bearings. Other objects will appear from time to time in the course of the specification and claims.

I illustrate my invention more or less diagrammatically in the accompanying drawings, wherein—

Figure 1 is a plan view;

Figure 2 is a section on the line 2—2 of Figure 1;

Figure 3 is a section on the line 3—3 of Figure 1;

Figure 4 is a section on the line 4—4 of Figure 2;

Figure 5 is a section on the line 5—5 of Figure 4;

Figure 6 is a section on the line 6—6 of Figure 3;

Figure 7 is a horizontal section through a variant form of the device;

Figure 8 is a plan view of a further variation;

Figure 9 is a section on the line 9—9 of Figure 8;

Figure 10 is a partial section on the line 10—10 of Figure 9;

Figure 11 is a vertical section with parts broken away, illustrating a still further variation of the device;

Figure 12 is a horizontal diagrammatic section of another modified form;

Figure 13 is a partial side view with the crushing bowl in section, of a still further variation; and

Figure 14 is a diagrammatic horizontal section of the device illustrated in Figure 13.

Like parts are indicated by like symbols throughout the specification and drawings.

Referring for example to the form of Figures 1 and 2, I generally indicate any suitable base upon which is mounted a circumferential frame member herein illustrated as in the form of a channel 2, with a bottom flange 3 engaging the base 1 and a top flange 4 to which may be bolted a supporting plate or spider 5 having a central sleeve 6. Mounted upon the upper flange 1 of this central sleeve 6 is a generally cylindrical motor housing 8. The details of the motor do not of themselves form part of the present invention but I indicate an impeller rotor shaft generally as 9, which, it will be understood, may be directly coupled to the motor, so that no transmission, gearing, belts, or separate driving means are necessary. 10 is any suitable upper housing or cover which shields the motor, and motor bearings. It rests upon the upper flange of the member 8. It is shown herein as having ears 11 which support the generally vertical rods 12 upon the upper ends of which is mounted a hopper or feed box 13 aligned with any suitable chute, spout or material delivery means 14. The bottom plate 15 of the hopper 13 receives the direct delivery of material 16 from the chute 14 and as it piles up it rolls down the twin vertical delivery passages 16, 17. In Figures 1 and 2, two of these passages are shown, diametrically opposed at an equal radial distance from the center of rotation of the motor. Each of these spouts passes at its lower end through an aperture 18 or 19 in the plate 5. The weight of the spouts may be at least in part supported by flanges 20 welded or otherwise secured to the lower ends thereof. Whereas we have shown in some of the drawings vertical chutes or spouts it will be understood, of course, that in the claims unless I limit myself specifically to the use of vertical spouts, inclined spouts or chutes may be employed as illustrated, for example, in Figure 12.

Positioned within the member 6 is a ring 25. Enclosed within it is a second and inner concentric ring 26. Between them is positioned a mass or ring of rubber or any suitable equivalent material 27 to serve as a floating support for the shaft bearings. The rubber is confined in place as by the bottom closure plates 28. The bolts 29 which hold it thus lock the floating suspension in place. 30 is an outer roller bearing race and 31 an inner race, the rollers 32 being positioned therebetween. The inner race is mounted upon the impeller shaft 9. It may, for example, be locked against the ledge 33 as by any suitable screw-threaded locking ring 34. The ring 34 may have a downwardly extending flange 35 which

overlaps the upwardly extending flange 36 of the plate 28. The result is a species of labyrinth but it will be understood that any other means may be employed for keeping dust out of the bearings. To protect the bearings from above I illustrate a further closure plate 38 which engages the enlarged portion 33 of the shaft 9. It may be provided with any suitable packing spaces 39.

Mounted on the lower end of the impeller shaft 9 is the impeller proper which I illustrate in Figure 6 as a body 40 having three projecting arms 41. It may be keyed to the shaft 9 as by keys 42 and any suitable locking means may be employed including the nut 43 as shown in Figure 2, for holding the impeller firmly in position upon the impeller shaft 9. Mounted in each of the arms 41 is an impact plate proper. I illustrate these plates in some detail in Figures 4 and 5. It is important that they be readily detachable. Referring to Figures 4, 5 and 6, each such plate includes a main impacting or body portion 50 with a forwardly extending inner side portion 51. Adjacent the juncture of 50 and 51 there is a rearward piece which may be roughly described as a dovetail 52, which penetrates a corresponding aperture 53. It is clamped therein as by a pair of wedges 54, 55, one being downwardly drawn and the other upwardly by rotation of the oppositely screwthreaded bolt 56 which is provided at top and bottom with washers 57 and lock nuts 58. It will be understood that the bolt 56 can be rotated from either end by the square end portions 59. Rotation in either direction moves the two wedges in relatively opposite directions. The wedges are half round in form, as shown in Figure 4, and are provided with inclined faces 60, opposed to corresponding faces 61 upon the member 50. The round portions of the bodies of the wedges seat in a rounded aperture 62 in the arm 41 which is really a continuation of the dovetail aperture 53 or opens on one side of it. Note that the impact surface of the member 51 is somewhat at an angle to that of the member 50. Also, the face of the member 50 is somewhat inclined to the true radius of the impeller. Furthermore, as is clear in Figures 3 and 6, it is set somewhat at an angle in relation to the axis of rotation of the impeller.

In order to have ready access to these impact members I illustrate the cover 5 as provided with apertures closed by closure plates 70 which are removably held in position as by bolts 71, as shown in Figure 3.

It will be understood that a rotation of the impeller will carry the faces of the member 50 at a high rate of speed through the path of the material dropping down the chutes 16 and 17, whereby the particles, falling freely under gravity, are impacted and are violently delivered along a generally horizontal direction. The first stage of reduction takes place by this impact, as the particles fall. The second stage reduction results from the impacting of these particles against fixed wear plates within the base or housing 2.

Referring, for example, to Figures 1 and 6, in the form of my device in which I employ an impeller with three arms in connection with two chutes, the material is impacted at two points by the impeller and is therefore delivered centrifugally outwardly along two separate paths or in two separate zones. The major portion of the material delivered is impacted against the wear plates 80 of Figure 6. These plates are

bevelled along their edges as at 81 and are wedged at their opposite edges as by wedges 82 controlled by bolts 83 which can be exteriorly actuated. The result of tightening the wedges 82 is to wedge the bevelled edge 81 firmly against the opposed portion 84 of the base 2. As the material is not delivered along a strictly limited path I provide a side plate 85 which is held in position as by bolts or screws 86. Top plates 87 are also employed, shown in dotted line in Figure 1 which are held in position as by bolts or screws 88. All the bolts and screws above described are accessible from the outside. However, in order to get access to the bolts for insertion or removal of the plates I provide removable top closure plates 89 which are held in position by the bolts or screws 90 whereby ready access may be had to the wear plates 80 and 85.

Referring to Figure 7 I illustrate a variant form of the device in which three chutes are indicated as 95, 96 and 97, evenly spaced about the path of the impeller. The impeller is provided with two arms 98 and 99 respectively. This reverses the arrangement of Figure 1 in which there were more impact members on the impeller than spouts. A wide latitude of arrangement is possible but it is important that the spouts and impeller members be of different numbers so that only one impact is being delivered at a time. In other words, whether two impact members are employed on the impeller or three, they are preferably so related in relation to the position and number of the chutes, that only one impeller is delivering a crushing impact at a time.

It will be noted that the capacity of the impact crusher is in direct proportion to the number of chutes conveying the material down into the path of the impact members 50 of the impeller. While the number of chutes is limited to an economical maximum, they may be so arranged that by doubling the number of chutes the capacity of the crusher may thereby be doubled. This may under some circumstances indicate that two streams of falling material may be impacted at the same time. Inasmuch as there is a fixed loss of power due to windage and friction, the advantage of increasing the number of chutes is to crush more material with the expenditure of power necessary to do such crushing and with little if any increase in unproductive power. It will be understood that the number of impeller arms or members may be chosen to suit the speed of the impeller and the number of chutes, and does not directly affect the capacity of the crusher. The capacity of the crusher is increased by increasing the number of chutes, not the number of impact members, but when the number of chutes has been selected, the number of impeller members 50 employed to get the desired result depends not merely upon the number of chutes but also the speed of rotation of the shaft 9.

Referring to the form of Figures 8, 9 and 10, I vary the arrangement of the form of Figure 1 and following by adding means for causing previously crushed oversized material to fall downwardly across the face of the wear plates 80. I illustrate, for example, separate feeding means for fine and coarse material. 100 is the feed box for the coarse material, which is in communication with the two vertical spouts 16 and 17. 101 is a spout for delivering previously crushed oversized material, for example screenings from the first pass through the machine. It delivers to a fine feed box 102 which is shown as having two

spouts 103 and 104 respectively, to supplemental feed boxes 105, 106, with ledges or shelves 107 to break the fall of the material. The material, after it is piled up on these shelves, drops down the final spout or delivery space 108 and falls thereby directly across the face of the wear plate 80. Therefore, as shown in Figure 10, the particles delivered from the impact surfaces 50, as at A in Figure 10 are directed against the gravitally falling particles indicated at B in Figure 10. These in the form of a sheet of fine particles, are therefore crushed against the plate 80, and receive a further reduction. This form of the device is particularly adapted to closed circuit crushing and it will be understood that any efficient form of conveying and screening may be employed, whereby certain desired intermediate sizes of material, finer than the original feed but coarser than the desired end product, are dropped in front of the plate A for a further secondary impact.

Figure 11 illustrates a variant form of my device in which the parts are transposed in such fashion that the motor housing 8 and its associated parts is positioned below the base 2. Any suitable discharge chutes 110 are illustrated, formed in what may if desired be a slotted base 112.

It will be realized that whereas I have described and shown a practical and operative device, nevertheless many changes may be made in the size, shape, number and disposition of parts without departing from the spirit of my invention. I therefore wish my description and drawings to be taken as in a broad sense illustrative and diagrammatic rather than as limiting me to my specific showing.

Referring to the form of device shown in Figure 12 I illustrate inclined chutes or spouts 16a which are adapted to direct the material downwardly toward the revolving impeller in a direction opposite to that of the rotation of the impeller, to produce better reduction in crushing. The impacted falling particles are affected not merely by the direct speed of rotation of the impact members 50 but by the additional lateral speed, in an opposite direction, caused by their delivery into the zone of impact in a direction opposite to that of the rotation of the impeller. Even an angle of 15 degrees from the vertical will produce a horizontal component of a considerable amount at the time the material leaves the bottom of the chute and enters the zone of impact.

Any satisfactory means may be employed for counterbalancing the impeller. Either the impeller arms supporting the members 50 are so distributed about the axis of rotation of the impeller as to maintain dynamic balance during rotation, or the parts may be weighted in any suitable fashion in order to prevent any undesired vibration resulting from the high speed rotation of the unbalanced member.

It will be understood that my device is particularly adaptable to closed circuit crushing. The product delivered gravitally downwardly from the crushing zone, for example, falling freely downwardly away from the faces of the plates 80 and 85 or the overhanging plate 87 may be taken in any suitable conveying and screening means. The fines may be separately disposed of and the oversized returned for recrushing. In the form of Figure 9 I illustrate means for recirculating some of the intermediate sized material by dropping it across the face of the plates 80. This is under some circumstances desirable but

it is not an inseparable feature of my device. In all forms of the device it will be noted the motor is positioned closely adjacent the impeller, the motor shaft serving as the impeller or impact shaft.

I might find it desirable to have more than one impact occur simultaneously and for exemplification I have illustrated in Figure 12 both the impact members 50 on the impeller 49 and the delivery chutes 16, 17 diametrically opposed to each other in relation to the axis of the shaft 9. It will be understood, however, that I may vary the number of arms 41 and associated impact members 50 and the number of chutes. Owing to the greater unevenness of torque, because of a plurality of simultaneous impacts, I may incorporate in conjunction with the impeller 40 a fly wheel 120 to eliminate heavy pulsation in the electrical circuit for actuating the motor. However, the greater the number of impact arms 41 and number of chutes, the less this effect would be felt.

For slow running motors a greater number of impeller arms 41 may be employed. For example, in connection with an impeller having two impact members 50 diametrically opposed to each other, five delivery chutes equally spaced radially may be employed for delivering a single crushing impact at a time, and, in the variant form illustrated in Figure 12, four delivery chutes 30 may be used.

In order to obtain a better crushing effect I may deliver the material to be crushed at an angle towards the revolving impeller as illustrated in Figures 13 and 14. The chutes 121 herein shown as mounted at an incline, say for example at an angle of about 15 degrees with the vertical, direct the gravitally falling particles in a direction opposed to that of the revolving impeller.

The use and operation of my invention are as follows:

Referring to the form of Figure 1 and following, I drop material by gravity freely along a plurality of paths, for example, along the chutes 16 and 17. Referring to Figure 7, I increase the number of paths to three, the chutes 95, 96 and 97. In both forms I employ an impeller having a plurality of impact members 50. These are rotated by any suitable motor at a high rate of speed. The rate of rotation may, for example, be as high as 1500 R. P. M. It is important that the rotor or impeller be rotated at such a rate that every particle which is impacted is so struck as to be shattered. In practice, the effect is almost that of an explosion of the particle. It is also important that the speed of drop of the material, as it enters the impacting zone, is such that each particle is carried fully or substantially fully into the path of the impact members 50, so as to be struck by a full face blow. For example, I find that chutes of a height of say eight to ten feet are satisfactory. It will be understood, of course, that a substantial variation may be made both in the speed of rotation of the impact members and in the height of the drop. It is important that the material drop freely and without packing.

By having the motor coupled directly to the impeller I avoid the necessity of the use of any intermediate drive, gear reduction or the like. The rubber blocks 27 serve as a vibration preventing means. The wear plates 80 and 85 are readily removed and access to them and to the impeller members is easily had by removal of the cover plates 70 and 89.

I claim:

1. In an impact crusher, a base, a rotor mounted upon said base to rotate about a vertical axis, a plurality of impact members peripherally spaced about said rotor, the impact face of said members having a surface whose vertical dimension is of the same order as its horizontal dimension, a plurality of substantially vertical feed spouts adapted to deliver material, at widely spaced points, to the path of movement of said impact members, and individual secondary fixed crushing plates laterally aligned with the zone of intersection of the path of feed from each spout with the path of movement of the impact members of the rotor, said secondary impact members being sufficiently spaced laterally from the path of movement of the rotor to permit the secondarily crushed particles to fall gravitally along a path removed from the path of movement of the impact members.
2. In an impact crusher, a base, a rotor mounted on said base for rotation about a generally vertical axis, means for rotating said rotor, a plurality of impact members mounted on said rotor and spaced peripherally thereabout, and a plurality of generally vertical tubular delivery chutes adapted to deliver the material to be crushed at the general level of and in the path of movement of said impact members, at a plurality of segregated delivery zones, one for each chute, said chutes being of sufficient height to impart a substantial gravitational acceleration to the delivered particles, the spacing of the impact members about said rotor being proportioned to the speed of the freely falling particles whereby substantially all particles penetrate into the path of said impact members before being impacted, and receive a full face impact, and secondary impact members, laterally removed from the rotor, adapted to receive the impacted particles centrifugally delivered by the rotor, said secondary impact members being spaced a sufficient distance from the rotor to permit the secondarily impacted particles to drop by gravity along a path removed from the zone of the primary impacting.
3. The structure of claim 2 characterized by the employment of a different number of impact members and chutes.
4. The structure of claim 2 characterized by the employment of a plurality of chutes and of a greater number of impact members than of 10 chutes.
5. The structure of claim 2 characterized by the positioning of the chutes, in relation to the distribution of the impact members about the rotor, in such fashion that the delivery from each chute is impacted at a time when the delivery from no other chute is being impacted.
6. The structure of claim 2 characterized by the employment of separate and distinct secondary impact members each positioned to receive the particles discharged from one of said chutes, after their impacting by the rotor.
7. The structure of claim 2 characterized in that the secondary impact members are so spaced in relation to the primary impact members that the ensuing delivery from the primary impact members of impacted particles causes a bombardment of the particles already impacted against the secondary impact members.
8. The structure of claim 2 characterized by the employment of chutes which are inclined somewhat against the direction of rotation of the rotor, whereby the particles are delivered for crushing in a direction opposed to the direction of rotation of said rotor.
9. The structure of claim 2 characterized by the employment of a like number of delivery chutes and impact members.
10. The structure of claim 2 characterized by the employment of a greater number of impact members than of chutes.

OSCAR C. GRUENDER.
